UNITED STATES PATENT OFFICE.

WILLIAM ERASTUS WILLIAMS, OF CHICAGO, ILLINOIS.

STEEL WHEEL.

1,131,883.

Specification of Letters Patent. Patented Mar. 16, 1915.

Application filed May 22, 1911, Serial No. 628,718. Renewed July 23, 1914. Serial No. 252,762.

To all whom it may concern:

Be it known that I, WILLIAM ERASTUS WILLIAMS, a citizen of the United States, residing at 601 Woodland Park, Chicago, in the county of Cook and State of Illinois, have invented a new and useful Improvement in Steel Wheels, of which the following is a specification.

My invention relates to that class of wheels wherein a sheet steel center or web is suitably connected to the rim and the hub. This center or web, formed in any suitable way, consists of a sheet metal disk provided with a central, hub-receiving, opening and having outwardly tapering, radial corrugations.

Wheels of the sheet disk pattern have heretofore been objectionable owing to the difficulty of securely fastening the disks to the hub and to the rim.

A very light weight of sheet metal may be used for the center or web of the wheel if a complete union of the sheet can be made with the hub and the rim such as I accomplish.

Reference will be had to the accompanying drawings in which—

Figure 1 is a perspective view of my corrugated sheet steel center; Fig. 2 is a central sectional cross-section of Fig. 1; Fig. 3 is a central cross-section through the finished wheel; Fig. 4 is a detail of a form of fastening device used with automobile wheels; Figs. 5 and 6 are perspective views of hub pieces before the parts are assembled; Fig. 7 is a detail in section showing the hub pieces assembled ready for being united together; Fig. 8 is the same as Fig. 7 after the parts are united; Fig. 9 is a detail in section of an alternative form of rim; Fig. 10 is a detail section of the rim showing the parts together but not united; Fig. 11 is the same as Fig. 10 after the parts are fastened or united together; Fig. 12 is a section through a complete wheel provided with a rim and hub such as is sometimes used for automobiles.

In the drawing, 1 designates my corrugated sheet steel center made of a uniform thickness of sheet and so corrugated that there is the said cross-sectional weight of metal on any circumference. These corrugations give great strength to the disk thus formed.

2 indicates the hub ring into which the corrugated disk is fastened; this ring 2 is

made of the pieces 3 and 4, which are provided with projections 5 and 6 which fit into the corrugations of the disk around the hub circumference. These rings 3 and 4 may be made in any suitable way but I prefer to make them of drop forgings or stampings.

In making the rings 3 and 4 of stampings, I may make them out of straight strips and then bend them into rings and weld their ends by electricity, or may use other methods. When the rings 3 and 4 are properly formed, they are placed in position over the corrugations of the disk at its center as in Fig. 7, and the inner marginal portion of the web and the adjacent parts of the hub are then fused or welded into an integral mass, as suggested in Fig. 8, by means of an oxygen-acetylene blow-pipe torch or other suitable means.

The thickness of the web or corrugated sheet is so slight that it is difficult to weld it as a butt-joint or lap weld as it heats and burns before the heavier metal to which it must be joined in a wheel, arrives at a welding temperature. But by joining the thin sheet on both sides by heavier stock to which the heat is applied, the thin sheet is protected from burning until the whole section is brought to the required temperature. This arrangement of the rings and sheet permits the welding from the hub hole and thus permits a complete union along the entire joint or seam 7, and saves any danger from oxidation or burning or drawing of the temper of the sheet center at the point 8 where there comes the severest strain on the metal of the sheet. After the welding of the joint along the line 7, the hub hole 9 may be bored out, clearing it of the bur of welding.

The rim or felly of my wheel may be any suitable rim or felly but I prefer to use a felly which may also be the rim or tire if desired, and be made chiefly of two forms. The preferred form shown is made of two rings of angle sections 10 and 11, Fig. 10, between which is clamped the periphery 12 of the corrugated disk or center. The other form is shown in Fig. 9 and consists of two rings of rectangular cross-section which clamp between them, the periphery 12 of the disk. After the angle rings 10 and 11 are placed upon the disk, I then proceed to spot weld the angles and disk as shown by spots 13. These spot welds may be made by any suitable means such as a blow torch as

described by holding the torch in one spot till a little pool of metal is melted at that point, but I prefer to use what is known as spot electric welding for this purpose. Spot welding may also be used with the form of felly shown in Fig. 9 but Fig. 9 does not show it. After the spot welds are made in the flanges that embrace the sheet steel center, I then weld by any suitable means or mechanism, the seam 14 Fig. 10 entirely around the wheel. I prefer to use the blow torch as described for this purposes, which melts a little pool 15, Fig. 11 of metal along the seam all the way around the rim of the wheel which is slowly revolved under the torch. This arrangement of the parts saves the burning and the oxidations of the thin sheet of the web as before described and makes a complete secure union of the parts. After the seam 14 is welded the rim may be turned, ground, or rolled to remove any bur that may be objectionable.

If an automobile tire rim or other extra tire or rim is to be used, it may be secured to the felly or wheel in any suitable manner but I prefer to weld it to the inner rim or felly by spot welds 16 like those as before described.

For automobile purposes it may be desirable to use an extra hub center such as is shown by 17 in Fig. 12; the ring 2 being fitted to the hub 17 up against a flange 18 and securely held there by a nut 19 which may be provided with flat spots for use with an ordinary wrench or holes for a spanner wrench. By this fastening a new wheel, rubber tire and all, may be quickly placed upon the hub as is sometimes done in place of changing rubber tires.

Instead of the fastening with the nut 19, I may use the fastening shown in Fig. 4 which is provided with a ring 20 held upon the hub by bolts or screws 21 passing through into the flange 18 of the hub piece 17, Fig. 12.

For light automobile wheels involving my invention it is necessary to consider only how thick the metal sheet center should be to resist accidental lateral indentation, the

least thickness on this account permissible 50 having ample load-supporting strength.

The welding feature of my invention may be used with advantage when plan sheets of metal are used to form the web of the wheel. 55

The hub or rim features may be used to advantage in combination with other features of wheel construction.

It is of importance that the edge of the body sheet is connected to the ring members 60 by welding or fusing and that those members overlap the body to some distance from the welding line and grip it mechanically, merely. By this construction, the gripped portion is allowed slight lateral movement 65 between the free marginal portions of the ring members and while the advantages of integral union are retained, vibrations and strains are not sharply localized so as to produce fatigue or crystallization. 70

What I claim is:

1. In a metal wheel, the combination with a centrally open sheet metal wheel body, of two annular, registering wheel members upon opposite faces, respectively, of the 75 marginal portion of said body, the marginal portion of said body being welded to the adjacent members and said members laterally supporting without attachment thereto an annular portion of the body alongside 80 the welding line.

2. In a metal wheel, the combination with two annular, registering wheel members, of a sheet metal wheel body having its marginal portion closely held between said 85 members and its edge, only, welded to both; whereby slight lateral yielding of the body at the margins of said members is permitted and the injurious effect of strains and vibrations is avoided. 90

I witness whereof I have hereunto subscribed my name at the city of Chicago on this 18th day of May, 1911, in the presence of two subscribing witnesses.

WILLIAM ERASTUS WILLIAMS.

WINFIELD S. WILLIAMS,
C. A. ROPER.
